United States Patent Office.

DANIEL H. WHITNEY, OF BLACK ROCK, NEW YORK, ASSIGNOR TO IRA P. HATHAWAY, AUGUSTUS F. BARTLETT, AND GEORGE MORRIS, OF EAST SAGINAW, MICHIGAN.

Letters Patent No. 95,296, dated September 28, 1869.

IMPROVEMENT IN MACHINE FOR MAKING SHINGLE-BOLTS.

The Schedule referred to in these Letters Patent and making part of the same.

To whom it may concern:

Be it known that I, DANIEL H. WHITNEY, of Black Rock, in the county of Erie, and State of New York, have invented a new and useful Improvement in Shingle-Bolting Machines; and I do declare that the following is a true and accurate description thereof, reference being had to the accompanying drawings, and to the letters of reference marked thereon, being a part of this specification, in which—

Figure 1 is an elevation of the front, and

Figure 2, an elevation of the right side of my machine.

Like letters indicate like parts in each figure.

The nature of this invention relates to an improved device for sawing shingle-bolts from sections of wood cut to the proper length.

It consists in a new and peculiar combination and arrangement of its several parts.

In the drawings—

A represents a pair of vertical posts or standards, connected at the top by a beam, to form a frame, secured to and resting in a bed-piece, B.

Journalled in this bed-piece, in the rear of the posts A, is a counter-shaft, C, on which are keyed two pulleys, D and E, of proper diameters.

F is the driving-shaft, journalled in proper bearings at the top of the posts A, and has keyed to it a pulley, G. This shaft is rotated continuously in any convenient manner.

H is a sash, sliding on guides I, secured in front of the posts A.

The sash is constructed with two horizontal bars, H, the side-bars or standards H', and an intermediate standard, H''.

J is a circular saw, secured on a mandrel, J', which revolves in boxes in the sides of the sash.

The mandrel is also provided with a pulley, K.

The sash and its attachments are counterbalanced by a counter-weight, shown in outline in fig. 2.

A cord, L, passing over a pulley near the top of the frame, engages with one end of the sash; its other, is secured to the weight.

Two of these weights are used, and are boxed in, on the inner sides of the posts A.

In the sash, on its rear side, above the saw-mandrel, is hung a shaft, M, rotating in boxes in the standards H' H''.

On this shaft is keyed a tightener-pulley, N, shown in dotted lines in fig. 2.

O are toothed racks, projecting upward from the sash.

P is a belt, running from the pulley G down under the pulley K, thence up over the tightener N, thence down under and around the pulley D, and up over the pulley G again.

By this arrangement of the belt on these pulleys, motion will be communicated from the shaft G to them, causing the saw to rotate, and allowing the sash to be moved up or down at will.

Q is a shaft, rotating in bearings q q' in the posts A, having on one end a pulley, R, rotated by a belt, S, from the pulley E on the counter-shaft.

The bearing q' is stationary, while the bearing q has a slight vertical play on its studs, being moved by the lever a through the connecting-rod b.

On the other end of the shaft Q is secured a friction-wheel, T.

Below the shaft Q is another shaft, U, having on its end a disk, V.

Projecting inward from the disk, is a hub, v, and flange v', which form friction-pinions when the friction-wheel T is in engagement with either of them.

On the shaft U are two pinions, u', which engage with the racks O, and cause them to move up or down as the friction-wheel T is brought in contact with the hub v or flange v' of the disk. Pressing down the lever a, the sash will be raised up; raising the lever, it will be fed down.

W is a saw-table, slotted to allow the saw to pass down through it.

In the centre of the table is a centre-spindle, X, raised and lowered from the plane of the table by a treadle, Y. On this spindle the lower end of the block is centred.

The operator taking a block, centres it on the spindle X, which he raises, by placing his foot on the treadle, holding its upper end steady with one hand; with the other, he raises the lever a, when the sash will be fed down by the mechanism described, and the saw cuts the bolt through with the grain from its front edge toward the centre. Depressing the lever a, the saw is withdrawn from the block; releasing the lever, the sash remains stationary. He then turns the block around on the spindle until he presents it so as to take a quarter out of the block at the next cut, to the best advantage in the saving of timber, and avoid any knots or shakes, repeating the operation until the block is quartered into bolts.

What I claim as my invention, and desire to secure by Letters Patent, is—

1. In combination with the sash H, the racks O and the feed-mechanism, consisting of counter-shaft C, pulleys E and R, belts S and P, shafts Q and U, friction-wheel T, disk V, provided with friction-hub v and flange v', the sliding box q, lever a, rod b, and the pinions u', the whole arranged and operating in the manner and for the purposes specified.

2. In combination with the foregoing parts, as herein described, the standards A, shaft F, pulleys G, N, K, and D; saw-table W, spindle X, and treadle Y, when constructed, arranged, and operating substantially as and for the purposes set forth.

DANIEL H. WHITNEY.
